INTERNAL COMBUSTION ENGINE

Desire J. Deschamps, St. Louis, Mo., assignor of
one-half to P. De C. Ball, St. Louis, Mo.

Application October 13, 1930, Serial No. 488,222

3 Claims. (Cl. 123—59)

This invention relates generally to two stroke internal combustion engines of the compression ignition type generally known as Diesel engines and more particularly to such engines which are adapted to operate at high speeds suitable for use in automobiles and aircraft.

Heretofore internal combustion engines of this type have been successfully operated at comparatively low speeds for industrial purposes, but such engines have not been capable of operation at the high speeds required for engines in aircraft and automobiles. The most important limiting features which prevent the use of such engines as have heretofore been known, for automotive purposes, are the fuel injection system and the distribution mechanism. In a two stroke cycle engine, power output and the specific fuel consumption are principally dependent upon the efficacy of scavenging of the cylinders. The scavenging must be accomplished in a relatively short time, during the short part of the stroke of the piston that the exhaust ports remain open, and this cannot be thoroughly accomplished by the methods heretofore employed in slow and medium speed engines. The prior distribution mechanisms and scavenging systems have not provided a sufficient section for the passage of the exhaust gases and the admission of the scavenging air, furthermore, the relative location of the inlet and outlet ports have caused the scavenging air to mix to some extent with the exhaust gases, and, consequently, on the next succeeding cycle the cylinder is partly filled with burned gases, so that efficient operation and complete combustion are impossible.

The object of this invention is, as generally stated, to provide a two-stroke internal combustion engine of the compression ignition type which is capable of operation at high speeds.

Another object of this invention is to provide a rotary sleeve valve mechanism for a two-stroke internal combustion engine which shall be operated at a speed less than the crank shaft speed of the engine.

A more specific object of this invention is to provide a valve mechanism which shall have a minimum number of moving parts.

Other objects of this invention will become apparent to those skilled in the art when the following description is read in connection with the accompanying drawings, in which:

Figure 1 is a view in side elevation, shown partly in section to reveal the operating parts

of an internal combustion engine constructed in accordance with this invention;

Figure 2 is a sectional view, taken along the line 2—2 of Figure 1;

Figure 3 is a view in side elevation showing particularly the manner of driving the sleeve valves of this invention;

Figure 4 is a perspective view of a valve element employed in accordance with this invention;

Figure 5 is a detail view in end elevation of an element for connecting the valve sleeve with its drive shaft; and

Figure 6 is a detail view in side elevation of the connecting element shown in Figure 5.

In accordance with this invention, a two-stroke internal combustion engine of the compression ignition type—that is an engine in which ignition takes place by the injection of a quantity of fuel into a chamber in which a definite volume of air has been highly compressed so that the temperature is sufficient to ignite the fuel—is provided with a rotary sleeve valve operating in a solid housing and at a speed less than the speed of the crank shaft of the engine and preferably at a speed equal to one-half of the crank shaft speed. If operated at half of the crank shaft speed, the valve is provided with diametrically opposite ports, which open upon each receding stroke of the piston to admit to the cylinder a quantity of slightly compressed air for removing the fumes from the cylinder and which operation is known as scavenging. As is customary in usual practice, the one piece valve housing and the rotary sleeve valve extend along over the head of the several cylinders of the engine, which necessitates the use of a very long valve in case of a multi-cylinder-in-line engine. In addition to the inherent difficulty of accurately machining such a long sleeve, experience has shown that in such a long valve housing and valve, slight distortions are caused by the uneven distribution of the heat to effect uneven expansion and contraction. These distortions may be of such extent as to slightly bend the valve or the housing and cause the valve to freeze in its housing by undue increase of local pressure between the valve and its housing.

The sleeve valve arrangement which is contemplated by this invention involves a plurality of sleeve sections having a uniform rotary movement in a "solid" housing, which acts as a bearing for the same. The sleeve sections are driven by a single slightly flexible drive shaft coaxial

therewith, through couplings centered in the bore of the valve elements and so mounted as to eliminate the possibility of so-called freezing between the valve elements and the housing within which they rotate. It will be apparent that by the division of the sleeve valve into a plurality of sections, relative movement between the sections is possible, so that no binding occurs incident to uneven expansion and contraction of the housing. As hereinbefore stated the cylindrical valve sleeves rotate in a solid housing. By the term "solid" housing it will be understood that the housing includes an integral cylindrical bore and that no special mechanical devices are used to control the running clearance between the valve and the housing at the various operating temperatures of the engine. The necessity for such mechanical devices is eliminated by this invention wherein use is made of especially selected metals for the construction of the rotary sleeve valve and its housing.

Referring now to the drawings, an internal combustion engine of the compression ignition type is shown in inverted position, in which 25 position it is preferably operated in aircraft.

The engine of this invention comprises a block having a plurality of cylinders 1, 10, etc., and within each cylinder is slidably mounted a piston 2 in a manner well known in the art. As 30 hereinbefore stated, the cylinders are in aligned relation within a cylinder block 3 so that the pistons 2 in each cylinder may transmit a power stroke to a common crank shaft. A head 4 is provided for closing the end of the cylinders 1, 35 10, etc., and is formed of a single casting extending across the entire block 3. Within the head 4, an integral cylindrical bore 5, extending longitudinally thereof, is formed so that the "solid" housing, hereinbefore mentioned, remains. The cylindrical housing 5 communicates with each of the cylinders 1, 10, etc., through ports 6, 60, etc., which extend through the wall of the head 4 so as to provide a passage 40 between the sleeve and the cylinder. The head 4 and the block 3 are each provided with jackets 45 having spaces 7 for the circulation of the cooling medium.

A slightly flexible shaft 8 is disposed coaxially within the bore 5 and is supported by a suitable bearing cap 9. It will be observed that the bearing cap 9 forms a closure for one end of the valve housing 5. A bevel gear 11 is secured to the shaft 8 at the end thereof outside the cap 9. A bevel gear 12 is mounted upon the end of a shaft 13 for cooperation with the bevel gear 11 to drive the shaft 8 by power from the crank shaft of the engine, which may be delivered to the shaft 13 through any suitable power-transmitting mechanism. It may be here pointed out that the power-transmitting mechanism employed with the embodiment illustrated in the drawings is such that the shaft 8 rotates at a speed equal to one-half of the speed of the crank shaft of the engine.

Within the cylindrical housing 5, a plurality of valve elements 14, 15, 16, are disposed each of which is adapted to serve a pair of adjacent cylinders, such as 1 and 10. For the purpose of illustration, these valve elements are provided 65 three in number, since the engine illustrated is of the six cylinder type. Each of the valve elements 14, 15, and 16, is mounted for a close running fit within the cylindrical housing 5, so that rotation of the element within the housing 70 is possible. As is clearly illustrated in Figures 1

and 4, the valve element 14 is provided with a pair of diametrically opposite openings 17 and 18 through the wall thereof, which are disposed directly above the port 6 through the wall of the cylinder head 4, and it will be clearly apparent that upon rotation of the valve element 14, the openings 17 and 18 will alternately come into such a position that a passage is opened between the inside of the valve element 14 and the cylinder 1. Since the valve element 14 10 serves two cylinders of the engine, another pair of diametrically opposite openings such as 19 is provided directly above the adjacent cylinder 10, which upon rotation of the element 14 will become disposed opposite the port 60 of the cylinder 10 to open a passage thereto at the proper time during the operating cycle of the cylinder 10.

Referring now particularly to Figure 4, it will be seen that the valve element 14 is provided 20 about its circumference with a plurality of circumferentially extending grooves 20, 21 and 22, located symmetrically on each side of the ports 17, 18 and 19. It will be noted that the grooves 20 are provided with angular extensions, such 25 as 23, extending from the groove toward the openings of the valve. The orientation of these angular extensions 23 is such that they operate to disperse lubricant by its inertia upon the rotation of the valve element 14, to thereby form 30 and maintain a film of lubricant between the outer wall of the rotary valve element 14 and the bore of the cylindrical housing 5.

In the wall of the valve housing 5 are drilled 35 a plurality of small calibrated holes which are in communication with a suitable oil line (not shown) extending along the outer wall of the valve housing 5, this oil line may be connected with the main lubricating system of the engine. One such calibrated hole is disposed directly 40 over each groove 20, so that lubricant is fed to the sleeve element 14 at the points indicated by arrows in Figure 4, filling the grooves 20 from which it is dispensed over the entire surface of the valve element 14. The other circumferential grooves 21 and 22 act as small oil reservoirs 45 and hydraulic rings which coat with the lubricating oil film to assure the sealing of the cylindrical valve element in its housing 5, so as to prevent the escape of gases to adjacent cylinders through the clearance between the walls of the housing 5 and the valve element 14 such as, for instance, between the ports 6 and 60. The disposition of these grooves is, of course, similar for each of the valve elements 14, 15 and 16 of 50 the engine.

The valve elements 14, 15 and 16 are each also provided with a plurality of longitudinally extending grooves such as 24, which are cut parallel to the openings 17, 18 and 19 and are located 60 at each side thereof. These grooves act as so many oil reservoirs operating to lubricate the bearing surfaces between the valve element and its housing. These longitudinal grooves have about the same length as the openings of ports 17 65 and 19, but do not communicate directly with the circular grooves 22. It will be noticed also that no longitudinal grooves 24 are provided on the portion of surface of the valve element 14, which covers the intake port 6 during the phase of the 70 cycle when the pressure in the combustion chamber of the cylinder is at its maximum value, that is when the piston 2 is at its top dead center position, at which time combustion of the injected fuel begins.

As clearly illustrated in Figure 4, each valve element is provided at one end with two slots 25 cut in its walls, which latter may be suitably reinforced at that place. The slots 25 are disposed to receive a tongue 26 of a coupling member such as 27 or 28. As shown in Figure 3, these coupling members 27 and 28 are keyed to the drive shaft 8 for rotation therewith. The coupling 27 drives both the valve elements 14 and 15, while the coupling 28 drives only the last valve element 16. Any number of valves may, of course, be driven by such connections. Where there is an even number of valves a coupling such as 27 may be arranged to drive each pair. Where there is an odd number of valves, the odd one may be driven by a coupling such as 28. As previously stated, the shaft 8 is supported near one end thereof in the bearing 9, so that the elasticity of the metal permits limited flexing of the extended portion within the housing 5. The shaft 8 is centered in the valve elements by the coupling members 27 and 28, which are provided with extensions 29, engage with a sliding fit within the bore of the valve element and cooperate with the tongue 26 to center the coupling in the valve element. The valve elements being thus in slidable engagement with the couplings 27 and 28, a limited axial movement of the valve elements relative to the shaft 8 is possible when the opposed ends of adjacent valve elements do not abut each other. With this arrangement, the valve elements are thus floating in the housing 5, being movable relative to each other as well as to the shaft 8. As pointed out hereinbefore, the shaft 8 is of a tubular and somewhat flexible construction; being substantially free at the end within the housing 5, it permits slight distortions of the valve housing 5 without affecting the seating or freedom of movement of the valve elements in the housing. In this way, the operation of the valve elements is not impaired by slight bending of the housing incident to uneven expansion and contraction.

Since it is necessary that the valve elements 14, 15, and 16 be rotatable within the cylindrical housing 5 and at the same time fitted therein with sufficient closeness to prevent the escape of gases from one cylinder through the housing 5 to an adjacent cylinder, and since both the valve elements and the cylinder head are subject to considerable expansion due to the heat of combustion within the engine; it is necessary that provision be made to maintain an even clearance between the valve element and the housing 5. Furthermore, since it is customary in engines of this type to water cool cylinder heads, the wall of the housing 5 will be constantly cooled by the circulation of water thereabout, and in this way the expansion of the valve elements will be greater than the expansion of the sleeve 5 which surrounds them. Although the valve elements dissipate some heat which they receive from the hot gases in the cylinder to the air which circulates through the valve elements and by contact with the cooled walls of the valve housing, it is apparent that less heat will be dissipated by the valve elements than is dissipated by the housing 5 to the cooling water and, accordingly, greater expansion will occur in the valve elements than occurs in the housing 5. In order to maintain the desirable clearance between the valve elements and the sleeve 5 under all temperature conditions, so that a close fit will exist between these elements to prevent the flow of

gases therebetween and to permit rotation of the valve elements, it is desirable that the casting which comprises the cylinder head 4 and the housing 5, be formed of a material having a higher coefficient of expansion than the valve elements and it has been found that an aluminum alloy is well adapted for use in this relation. Since, as previously pointed out, the valve elements become heated to a higher temperature than the surrounding sleeve 5, the valve elements are preferably formed of a metal having a lower coefficient of expansion than the housing 5, and heat treated hard alloy steel has been found to be well suited for this purpose. By thus providing a valve element of hard steel and an outer bearing or housing of a suitable aluminum alloy for snug engagement therewith, within which the element is rotatable, it will be found that as the temperature of the valve element increases heat is delivered to the aluminum housing 5 to cause expansion thereof; and although the sleeve 5 is at a lower temperature than the valve element 14, the amount of expansion which takes place in the sleeve 5 is, due to its higher coefficient of expansion, substantially equal to the amount of expansion which takes place in the valve elements, so that the fit between these parts is not changed. Furthermore, the bearing qualities of these metals are such as to be extremely desirable for conjoint use.

A plurality of exhaust ports 31 are provided about the wall of the cylinder 1 in such a position that they will be opened by the downward movement of the piston 2 when approaching the end of its travel; and it will be understood that the power-transmitting mechanism between the crank shaft of the engine and the shaft 8 is such that one of the openings 17 or 18 in the valve sleeve 14 comes into engagement with the port 6 shortly after the time when the exhaust ports are opened by the movement of the piston 2.

In the operation of an internal combustion engine provided with a valve of this sort, a supply of slightly compressed air is admitted to an elbow 30 at one end of the housing 5 and delivered within the valve element 16. It will thus be seen that the valve elements 14, 15 and 16 act as a conduit for conducting slightly compressed air to the various cylinders upon the opening of the inlet ports 6 thereof. It will be recalled that in the embodiment illustrated, the valve elements 14, 15, and 16 are rotated by the drive shaft 8 at a speed equal to half the speed of rotation of the crank shaft of the engine, and it is thus apparent that each time the piston 2 of the cylinder 1 approaches the position indicated in Figure 1, one of the openings 17 or 18 will come adjacent the inlet port 6 to permit an inrush of scavenging air from the valve element 14 to blow the exhaust gases to the exhaust ports 31 and fill the cylinder 1 with clean air.

The air inlet port 6 opens a certain time after the exhaust ports 31 are opened by the downward movement of the piston, by this fact the exhaust period becomes thus divided in two distinct periods. The first period, which can be called the exhaust period at high pressure, extends from the moment the exhaust ports 31 are opened until the air inlet port 6 is opened. During that period the greater part of the burned gases escape through the exhaust ports, being forced out by the high pressure still remaining in the cylinder after the combustion of the fuel. The second period, which is much longer than

the first one, begins at the opening of the port 6 to permit the inrush of the slightly compressed scavenging air; this scavenging air travels toward the exhaust ports 31, forcing the remainder of the burned gases out of the cylinder.

When the piston 2 nears its top dead center position—or, in other words, when the crank shaft of the engine has rotated through 180 degrees, a supply of fuel is injected into the cylinder 10 through one of the nozzles 39 in a manner more fully described in my copending application Serial No. 482,956 filed September 19, 1930.

Since it is apparent that many modifications will present themselves to those skilled in the art and that many sub-combinations are of utility without reference to other features or sub-combinations, it is to be distinctly understood that such modifications and sub-combinations as do not depart from the spirit of this 20 invention, although not specifically described herein, are contemplated by and are within the scope of the appended claims. It is to be furthermore understood that the embodiment here shown and described shall be considered as merely illustrative and not in a limiting sense.

Having thus described the invention, what is claimed is:

1. A valve mechanism for a two-stroke internal combustion engine, comprising, a cylindrical housing having ports communicating with the cylinders of the engine, a plurality of valve elements disposed coaxially within said housing,

a cantilever shaft supported at one end of said housing for rotating said elements in unison, and means for centering the free end of said shaft within said housing.

2. A valve mechanism for an internal-combustion engine, comprising a cylindrical housing having ports communicating with the cylinders of the engine, a plurality of successively positioned valve elements disposed coaxially for independent alinement in said housing and having 10 ports cooperating with said first ports, and a single driving element to which each of said successive valve elements is individually and loosely connected so as to permit such independent alinement, said driving element being thereby 15 connected to drive all of said valve elements simultaneously and in fixed relation with each other.

3. In an internal combustion engine of the character described having a plurality of longitudinally arranged cylinders, a valve housing having a bore extending along the line of cylinders and having ports communicating with each of the cylinders, and a valve coaxially mounted for rotation in said bore, said valve having a 20 circumferentially continuous part snugly fitting said bore intermediate said ports, said housing being constructed of a metal having a greater coefficient of thermal expansion than the metal 25 of which the valve is constructed.

DESIRE J. DESCHAMPS.
